United States Patent Office

Des. 179,398
Patented Dec. 11, 1956

179,398

SOUND RECORDER

Henry A. Sherwood, Woodbridge, Conn.

Application June 22, 1955, Serial No. 36,638

Term of patent 14 years

(Cl. D26—14)

Fig. 1.

Fig. 2.

Fig. 3.

Fig. 4

Fig. 1 is a front perspective view of the sound recorder embodying my new design;

Fig. 2 is a rear elevational view of the sound recorder;

Fig. 3 is an enlarged front elevational view of the sound recorder; and

Fig. 4 is a side elevational view taken from the left of Fig. 1.

I claim:

The ornamental design for a sound recorder, as shown.
